US0D1057540S

(12) **United States Design Patent** (10) **Patent No.:** **US D1,057,540 S**
(45) **Date of Patent:** **** Jan. 14, 2025**

(54) **UTILITY KNIFE**

(71) Applicant: **Milwaukee Electric Tool Corporation**,
Brookfield, WI (US)

(72) Inventors: **Scott M. Hangartner**, Richfield, WI
(US); **Andrew M. Tuchscherer**,
Wauwatosa, WI (US)

(73) Assignee: **Milwaukee Electric Tool Corporation**,
Brookfield, WI (US)

(**) Term: **15 Years**

(21) Appl. No.: **29/878,933**

(22) Filed: **Jun. 29, 2023**

Related U.S. Application Data

(62) Division of application No. 29/795,611, filed on Jun. 18, 2021, now Pat. No. Des. 995,261, which is a division of application No. 29/703,769, filed on Aug. 29, 2019, now Pat. No. Des. 925,323.

U.S. Appl. No. 29/703,774, filed Aug. 29, 2019, Hangartner et al.

Primary Examiner — Philip S Hyder

(74) *Attorney, Agent, or Firm* — Reinhart Boerner Van Deuren s.c.

(57) **CLAIM**

The ornamental design for a utility knife as shown and described.

DESCRIPTION

FIG. 1 is a top, right, perspective view of a utility knife, showing the new design.

FIG. 2 is a front view of the utility knife of FIG. 1.

FIG. 3 is a rear view of the utility knife of FIG. 1.

FIG. 4 is a right view of the utility knife of FIG. 1.

FIG. 5 is a left view of the utility knife of FIG. 1.

FIG. 6 is a top view of the utility knife of FIG. 1.

FIG. 7 is a bottom view of the utility knife of FIG. 1.

FIG. 8 is a top, right, perspective view of the utility knife of FIGS. 1 through 8, depicted using a wire frame drawing technique.

FIG. 9 is a front view of the utility knife of FIG. 8.

FIG. 10 is a rear view of the utility knife of FIG. 8.

FIG. 11 is a right view of the utility knife of FIG. 8.

FIG. 12 is a left view of the utility knife of FIG. 8.

FIG. 13 is a top view of the utility knife of FIG. 8; and,

FIG. 14 is a bottom view of the utility knife of FIG. 8.

1 Claim, 12 Drawing Sheets
